CLASSROOM CABINET WITH SWINGING PAPER TRAY

Wilhelm W. Brockway, Los Angeles, Calif.

Application August 4, 1958, Serial No. 752,904

13 Claims. (Cl. 312—304)

This invention relates to classroom cabinets and has as its general object to provide an improved cabinet for the storage of paper in sheet form (typewriter paper, drawing paper, composition paper, etc.).

In general, the invention contemplates a cabinet provided with a plurality of storage trays that are mounted for vertical swinging movement between horizontal positions in which the trays may project through the open front of the cabinet, and storage positions wherein the trays are inclined downwardly and rearwardly within the cabinet and thus accommodated within the cabinet enclosure although of too great a width from front to rear to be thus accommodated when in horizontal positions. In one of its forms, the invention further contemplates such a cabinet structure wherein the trays, in their horizontal positions, may be extended, by sliding, through the open front of the cabinet to facilitate the handling of paper stock carried by the trays.

Other objects and advantages will become apparent in the ensuing specifications and appended drawing in which:

Fig. 1 is a vertical front to rear sectional view of a storage cabinet embodying my invention in a preferred form thereof;

Fig. 2 is a fragmentary horizontal sectional view taken on the line 2—2 of Fig. 1;

Fig. 3 is a vertical sectional view taken on the line 3—3 of Fig. 1;

Fig. 4 is a detail horizontal sectional view taken on the line 4—4 of Fig. 1;

Fig. 5 is a fragmentary vertical front to rear sectional view of a modified form of the invention; and

Fig. 6 is a detail horizontal sectional view taken on the line 6—6 of Fig. 5.

Referring now to the drawings in detail, I have shown therein, as an example of one form in which the invention may be embodied, a classroom cabinet embodying, in general, a fixed housing structure A adapted to rest upon a floor or a suitable supporting stand; a tilting-slide assembly B mounted within the housing A for tilting movement between the positions indicated in full lines and dotted lines respectively; and a series of trays C mounted in respective pairs of ways 13 of assembly B.

The invention in its preferred form provides for fixing the trays C to the rails 13 of assembly B, and such construction may be regarded as being represented by the full line showing of the trays in Fig. 1. As an optional alternative, the trays, instead of being secured to the rails 13, may be each independently slidable in their respective section of the slide rail assembly B, for extension to positions indicated by the horizontal broken lines. Trays C are adapted to be tilted along with the assembly B.

The housing A comprises a back panel 10, a pair of side panels 11, a door frame 12 defining an open front, a suitable base or stand (not shown because it may be entirely conventional) for supporting the housing A upon a classroom floor; and a suitable cover or cap which likewise is not shown because it may be of strictly conventional construction.

2

The slide assembly B includes several pairs of ways 13 of channel section disposed adjacent respective side panels 11; a pair of vertical mounting bars 14 to which the respective ways are pivotally attached near their forward ends by means of pivots 15; and a pair of slide bars 16 to which the rear ends of the respective rails 13 are pivotally attached by means of pivots 17. Secured to the respective side panels 11, immediately adjacent the rear panel 10, are a pair of vertical guides 18 in which the slide bars 16 are retained and guided for vertically sliding movement. Also secured to the respective inner faces of side panels 11 are horizontal rails 19, interposed immediately between the respective mounting bars 14 and adjacent side panels 11. A pair of rollers 20, each attached to a respective mounting bar 14 between the latter and a respective rail 19, are received in the respective rails 19 for horizontally rolling movement therein to accommodate bodily inward and outward movements of mounting bar 14 with respect to the housing A. The rails 19 are of channel section as disclosed in Fig. 3, and the rollers 20 are received therein for rolling movement upon the lower flanges thereof.

Referring now to Fig. 4, the vertical slide bars 16 are of "hat" section (modified channel section including a channel body portion 21 and marginal flanges 22 projecting outwardly from the open side of channel 21). The vertical guides 18 are of C section, each including a flat back web 23 secured to a respective side panel 11 of the housing, and a pair of narrow channels 24 receiving and slidably mounting the respective flanges 22. The pivots 17, as disclosed in Fig. 4, may be of a shouldered type, including a relatively small diameter stem 25 riveted into the web of channel section 21, a larger diameter trunnion section 26 rotatably received in a cylindrical aperture in the web of a respective way 13, and a head 27 engaging the inner face of the web to attach the same to the slide bar 16. Similar rivet type pivots 15, with stems 25 riveted into the respective mounting bars 14 and enlarged trunnion bodies 26 rotatable in cylindrical apertures in ways 13, may constitute the pivots 15 connecting the slideways 13 to the mounting bars 14 as shown in Fig. 3.

Each tray C comprises a bottom panel 28, a pair of sides 29, and a rear end member 30 which is slanted forwardly and upwardly, substanding with the respective bottom panel 28 a dihedral angle corresponding to the angle (e.g. 45°) at which the trays are tilted in their stored positions, illustrated in broken lines in Fig. 1. In this stored position, the sheets of paper, tending to slide rearwardly and downwardly, will be supported against the back member 30.

The respective side extremities of bottom panels 28 project laterally and are slidably received within the ways 13 which are of rectangular channel section as shown (see Fig. 3). These projecting side portions of bottom panels 28 constitute slide flanges 31 which are received in the respective ways 13, whereby the trays C are securely mounted in the slideways 13. Where the trays are mounted for horizontal sliding movements, the flanges 31 constitute slides and are slidably mounted in slideways 13.

In the operation of the trays C and their supporting mechanism B, the trays C may normally be disposed in the positions shown in full lines in Fig. 1, with their rear ends engaging stops 32 in the rear ends of ways 13; and when all trays are thus positioned, the entire assembly of trays and supporting mechanism may be tilted from the horizontal position shown in full lines to the downwardly and rearwardly tilted positions shown in broken lines. Whereas in the horizontal positions, the trays will extend through the open front of the cabinet as shown in full lines, the downwardly tilted positions enable the trays to be retracted entirely within the cabinet as indicated by the broken lines. Such retraction of the trays is effected

by a bodily inward shifting of the mounting bars 14, with their rollers 20 traveling in rails 19, as the vertical slide bars 16 are simultaneously shifted downwardly from positions of maximum elevation shown in full lines in Fig. 1 to downward limits shown in broken lines in Fig. 1. Thus, while the rearward extremities of rails 13 and trays C move in a vertical plane without any horizontal shifting movement, the forward extremities of the guideways 13 and trays C will be drawn into the cabinet because of the foreshortening of the horizontal distance between the respective bars 14 and 16, resulting from the downward tilting movement.

Where the trays are mounted for sliding movement in ways 13, they may be extended by such sliding movement to the positions shown in horizontal broken lines in Fig. 1.

The downward tilting movement may be effected by grasping the forward portion of one of the tray bottoms 28 in the hands and applying a downward twisting movement thereto while simultaneously pushing rearwardly thereon.

Conversely, when it is desired to open the cabinet and extend the trays for convenient access to their contents, the operator may grasp the forward portion of one of the trays with one hand, place the other hand beneath the lowermost tray at a point well to the rear of the mounting bars 14 and press upwardly against the bottom.

In the preferred form of the invention shown in Figs. 1-4, inclusive, the invention contemplates, in lieu of a complete counterbalancing of the trays about their pivots 15, the use of frictional engagement of the tray support ways 13 against the inner faces of mounting bars 14, developed as by setting the rivets or bolts 15 tightly to clamp the engaged members to one another, or by the use of thin friction washers (not shown) between the opposed faces of members 13 and 14 to provide a controlled frictional holding action sufficient to overcome the downward tilting force developed by the weight of the trays and slide bars 16 on the rear side of the axis of pivots 15 as overbalanced against the weight of the portions of the trays forwardly of the pivot axes. Thus the manual operating force applied to the trays in tilting them both downwardly and upwardly, is utilized to shift them between their respective positions, and the trays when released will remain in the position to which they have been moved. To minimize the need for such frictional holding means, the axes of pivots 15 may be disposed more nearly at the midway point between the front and rear margins of the trays (as by locating the mounting bars 14 and slide rails 19 closer to the back of the cabinet than the position shown in Fig. 1) so that only a slight excess of weight in the rear portions of the assembly over that forwardly of the pivot axes of pivots 15, need be handled by the frictional holding means.

Figs. 5 and 6 disclose a modified form of the invention wherein counterbalancing of the tray assembly is provided by a pair of yieldable supporting springs 35 disposed in the vertical channel spaces between slide bars 16 and vertical guides 18 (Fig. 6); each of the springs 35 having its upper end anchored at 36 to a respective guide 18 and having its lower end anchored at 37 to a respective slide bar 16. The loading value of springs 35 is just sufficient to support the excess weight of the tray assemblies rearwardly of pivots 15 when the tray assemblies are in the raised position of the ways 13 shown in Fig. 5, and in the downwardly tilted positions the increase in the load value of the springs due to their extension (coil springs being typically of a positive rate or increasing load value as they are extended) is compensated by the shift in the balance of load in the trays as normally loaded, toward the back of the cabinet as the trays are tilted downwardly, the center of load being distributed above the axes of pivots 15 in the raised positions of the trays; and will be further compensated by friction in the pivot joints of the tray assembly. I find however that the preferred method of counterbalancing is to properly dis-

tribute the weight of the trays fore and aft of the pivots 15, with a moderate excess of load rearwardly thereof, and to utilize a moderate amount of friction in the pivots 15 for holding action.

I claim:

1. In a tilting-tray cabinet, in combination: a housing having a back panel and side panel and an open front; a plurality of article trays each having slide flanges at the respective sides thereof; a plurality of pairs of slideways of channel section with open inner sides each receiving a respective slide flange whereby each tray is mounted for fore-aft sliding movement in a respective pair of slideways; a pair of vertical slide bars to which the rear ends of the respective slideways are pivotally attached; a pair of vertical slides attached to the respective side panels of the housing immediately adjacent the rear panel thereof and receiving the respective vertical slide bars for vertically sliding movement thereof whereby the rear ends of the respective pairs of slideways and their trays may be tilted downwardly; a pair of vertical supporting bars to which the respective slideways are pivotally attached adjacent their forward ends; a pair of horizontal rails secured to the inner faces of the respective side panels of the housing; and rollers attached to the respective mounting bars and engaged in the respective rails between the latter and said mounting bars and adapted to roll in the respective rails for supporting said mounting bars for bodily inward and outward movements with respect to the open front of said housing, following the downward tilting movements and upward return movements of the rear ends of the respective slideways.

2. Apparatus as defined in claim 1, wherein said vertical guides are of C-channel section with respective channel flanges at the respective sides thereof and wherein said vertical slide bars are of hat section each including a channel section body portion and a pair of marginal flanges at the open sides thereof, said marginal flange being slidably received in the respective channel flanges of said vertical guides.

3. In a tilting-tray cabinet, in combination: a housing having an open front; a plurality of article trays each having slide means at the respective sides thereof; a plurality of pairs of slideways each cooperating with respective slide means whereby each tray is mounted for fore-aft sliding movement; a pair of vertical slides on the respective sides of the housing immediately adjacent the rear thereof; means on the rear ends of the respective slideways cooperating with the respective vertical slides for vertically sliding movement whereby the rear ends of the respective pairs of slideways and their trays may be tilted downwardly; a pair of vertical supporting bars to which the respective slideways are pivotally attached adjacent their forward ends; a pair of horizontal rails secured to the inner faces of the respective side panels of the housing; and means on the respective mounting bars and cooperating with the respective rails for supporting said mounting bars for bodily inward and outward movements with respect to the open front of said housing, following the downward tilting movements and upward return movements of the rear ends of the respective slideways.

4. In a tilting-tray cabinet, in combination: a housing having an open front; a plurality of article trays each having slide means at the respective sides thereof; a plurality of pairs of slideways each cooperating with respective slide means whereby each tray is mounted for fore-aft sliding movement; a pair of vertical slides on the respective sides of the housing immediately adjacent the rear thereof; vertical slide means on the rear ends of the respective slideways cooperating with the respective vertical slides for vertically sliding movement whereby the rear ends of the respective pairs of slideways and their trays may be tilted downwardly; a pair of vertical supporting bars to which the respective slideways are pivotally attached adjacent their forward ends; a pair of

horizontal rails secured to the inner faces of the respective side panels of the housing; means on the respective mounting bars and cooperating with the respective rails for supporting said mounting bars for bodily inward and outward movements with respect to the open front of said housing, following the downward tilting movements and upward return movements of the rear ends of the respective slideways; and spring means acting between said slideways and the respective vertical slide means, spring-loading said slideways for downward tilting movement.

5. In a tilting-tray cabinet, in combination: a housing having a back panel and side panel and an open front; a plurality of article trays each including a pair of side members, a back member, a bottom panel secured to and projecting laterally beyond said side panels, to provide slide flanges at the respective sides thereof; a plurality of pairs of slideways of channel section with open inner sides each receiving a respective side flange whereby each tray is mounted for fore-aft sliding movement in a respective pair of slideways; a pair of vertical slide bars to which the rear ends of the respective slideways are pivotally attached; a pair of vertical slides attached to the respective side panels of the housing immediately adjacent the rear panel thereof and receiving the respective vertical slide bars for vertically sliding movement thereof whereby the rear ends of the respective pairs of slideways and their trays may be tilted downwardly; a pair of vertical supporting bars to which the respective slideways are pivotally attached adjacent their forward ends; and a pair of horizontal rails secured to the inner faces of the respective side panels of the housing; and rollers attached to the respective mounting bars and engaged in the respective rails between the latter and said mounting bars and adapted to roll in the respective rails for supporting said mounting bars for bodily inward and outward movements with respect to the open front of said housing, following the downward tilting movements and upward return movements of the rear ends of the respective slideways.

6. In a tilting-tray cabinet, in combination: a housing having a back panel and side panel and an open front; a plurality of article trays each including a pair of side members, a back member, a bottom panel secured to and projecting laterally beyond said side panels, to provide slide flanges at the respective sides thereof; a plurality of pairs of slideways of channel section with open inner sides each receiving a respective slide flange whereby each tray is mounted for fore-aft sliding movement in a respective pair of slideways; a pair of vertical slide bars to which the rear ends of the respective slideways are pivotally attached; a pair of vertical slides attached to the respective side panels of the housing immediately adjacent the rear panel thereof and receiving the respective vertical slide bars for vertically sliding movement thereof whereby the rear ends of the respective pairs of slideways and their trays may be tilted downwardly; a pair of vertical supporting bars to which the respective slideways are pivotally attached adjacent their forward ends; and a pair of horizontal rails secured to the inner faces of the respective side panels of the housing; and rollers attached to the respective mounting bars and engaged in the respective rails between the latter and said mounting bars and adapted to roll in the respective rails for supporting said mounting bars for bodily inward and outward movements with respect to the open front of said housing, following the downward tilting movements and upward return movements of the rear ends of the respective slideways, and coil springs acting in tension between said slideways and the respective vertical slide bars, spring-loading said slideways for downward tilting movement.

7. In a tilting-tray cabinet, in combination: a housing having a back panel and side panel and an open front; a plurality of article trays each including a pair of side members, a back member, a bottom panel secured to

and projecting laterally beyond said side panels, to provide slide flanges at the respective sides thereof; a plurality of pairs of supports of channel section with open inner sides each receiving a respective slide flange whereby each tray is mounted in a respective pair of supports; a pair of vertical slide bars to which the rear ends of the respective supports are pivotally attached; a pair of vertical slides attached to the respective side panels of the housing immediately adjacent the rear panel thereof and receiving the respective vertical slide bars for vertically sliding movement thereof whereby the rear ends of the respective pairs of slideways and their trays may be tilted downwardly; a pair of vertical supporting bars to which the respective slideways are pivotally attached adjacent their forward ends; a pair of horizontal rails secured to the inner faces of the respective side panels of the housing; and rollers attached to the respective mounting bars and engaged in the respective rails between the latter and said mounting bars and adapted to roll in the respective rails for supporting said mounting bars for bodily inward and outward movements with respect to the open front of said housing, following the downward tilting movements and upward return movements of the rear ends of the respective slideways.

8. A cabinet as defined in claim 7, wherein said flanges are secured in said supports.

9. In a tilting-tray cabinet, in combination: a housing having a back panel and side panel and an open front; a plurality of article trays; a pair of vertical slide bars to which the rear ends of the respective trays are pivotally attached; a pair of vertical guides attached to the respective side panels of the housing immediately adjacent the rear panel thereof and having guiding engagement with the respective vertical slide bars for vertically sliding movement thereof whereby the rear ends of the respective pairs of trays may be tilted downwardly; a pair of vertical supporting bars to which the respective trays are pivotally attached adjacent their forward ends; a pair of horizontal rails of channel section secured to the inner faces of the respective side panels of the housing; and rollers attached to the respective mounting bars, received in the respective rails between the latter and said mounting bars and adapted to roll in the respective rails for supporting said mounting bars for bodily inward and outward movements with respect to the open front of said housing, following the downward tilting movements and upward return movements of the rear ends of the respective trays.

10. In a tilting-tray cabinet, in combination: a housing having a back panel and side panel and an open front; a plurality of article trays; a pair of vertical slide bars to which the rear ends of the respective trays are pivotally attached; a pair of vertical guides attached to the respective side panels of the housing immediately adjacent the rear panel thereof and receiving the respective vertical slide bars for vertically sliding movement thereof whereby the rear ends of the respective pairs of trays may be tilted downwardly; a pair of vertical supporting bars to which the respective trays are pivotally attached adjacent their forward ends; a pair of horizontal rails secured to the inner faces of the respective side panels of the housing; and means on the respective mounting bars engaged with the respective rails for supporting said mounting bars for bodily inward and outward movements with respect to the open front of said housing, following the downward tilting movements and upward return movements of the rear ends of the respective trays.

11. A cabinet as defined in claim 10, wherein the assembly of trays is moderately unbalanced with an excess of weight rearwardly of the pivotal connections between the trays and said vertical supporting bars, and wherein said pivotal connections embody frictional holding means for resisting self-tilting of the trays downwardly from a raised position.

12. In a tilting-tray cabinet, in combination: a housing having a back panel and side panel and an open front; a plurality of article trays; a pair of vertical slide bars to which the rear ends of the respective trays are pivotally attached; a pair of vertical guides attached to the respective side panels of the housing immediately adjacent the rear panel thereof and receiving the respective vertical slide bars for vertically sliding movement thereof whereby the rear ends of the respective pairs of trays may be tilted downwardly, said vertical guides being of C-channel section with respective channel flanges at the respective sides thereof and said vertical slide bars being of hat section each including a channel section body portion and a pair of marginal flanges at the open sides thereof, said marginal flange being slidably received in the respective channel flanges of said vertical guides; a pair of vertical supporting bars to which the respective trays are pivotally attached adjacent their forward ends; a pair of horizontal rails secured to the inner faces of the respective side panels of the housing; and means on the respective mounting bars engaged with the respective rails for supporting said

15

10

20

mounting bars for bodily inward and outward movements with respect to the open front of said housing, following the downward tilting movements and upward return movements of the rear ends of the respective trays.

13. A cabinet as defined in claim 12, wherein the assembly of trays is unbalanced with an excess of weight rearwardly of the pivotal connections between the trays and said vertical supporting bars, and including resilient, yielding tension elements disposed between said hat section slide bars and said C-channel section guides, each tension element having its upper end secured to a respective guide and its lower end secured to a respective slide bar for supporting said excess of weight.
